UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

ELASTIC-FLUID TURBINE.

1,378,464.

Specification of Letters Patent.

Patented May 17, 1921.

Application filed October 29, 1920. Serial No. 420,502.

To all whom it may concern:

Be it known that I, OSCAR JUNGGREN, a citizen of the United States, residing at Schenectady, county of Schenectady, State 5 of New York, have invented certain new and useful Improvements in Elastic-Fluid Turbines, of which the following is a specification.

The present invention relates to elastic 10 fluid turbines and particularly to rotor structures which comprise a ring of buckets fastened to a disk or drum at their inner ends and having their outer ends connected together by a sectional bucket cover. In 15 such structures each bucket cover section spans a number of buckets and is fastened thereto by tenons formed integral with the buckets or by other suitable means and the ends of adjacent bucket cover sections are 20 spaced slightly apart to permit of expansion and contraction. This divides the ring of buckets into groups each group having a bucket cover and I have found, particularly in the case of long buckets, such as are 25 found at the low pressure end of a turbine, that the groups of buckets thus formed have a tendency to vibrate either on account of their natural period or due to inequalities of elastic fluid pressure. Such vibrations 30 may cause failure of buckets and the object of my present invention is to provide an improved structure and arrangement for preventing their occurrence.

For a consideration of what I believe to 35 be novel and my invention, attention is directed to the accompanying description and the claims appended thereto.

In the drawing, Figure 1 is a side elevation partly in section of a part of a turbine rotor embodying my invention; Fig. 2 40 is a top plan view of several adjacent buckets; Fig. 3 is a perspective view of a tie plate; and Figs. 4, 5 and 6 are views similar to Figs. 1, 2 and 3 of another form of the 45 invention.

Referring to the drawing, 5 indicates a rotor and 6 a ring of buckets fastened thereto at their bases and having their outer ends connected together by bucket cover sections 7, the buckets being provided with integral tenons 8 by means of which the bucket cover sections are fastened in position. This divides the ring of buckets into groups, the buckets of each group having

their outer ends fastened together by a 55 bucket cover section.

Now, according to my invention, I tie adjacent bucket groups together by means of flexible connections or tie plates such connections being located beneath the bucket 60 cover so as not to be in a position where they might get worn off or where they will impair the clearances. In the arrangement shown in Figs. 1, 2 and 3 the flexible connections are in the form of flat plates 9 65 reversely bent to form a U-shaped part 10. In the plates are openings 11 through which the tenons on adjacent buckets pass. The flexible connections are thus riveted in place directly beneath the bucket cover sections 70 by the same tenons which hold the bucket cover sections. This arrangement is well adapted for use where the outer ends of the buckets are comparatively close together.

When the outer ends of the buckets are 75 some distance apart, I may use either the arrangement shown in Figs. 1, 2 and 3 or I may use that shown in Figs. 4, 5 and 6 wherein the flexible connections 12 are riveted directly to the adjacent ends of the 80 bucket cover sections by rivets as indicated at 13. In this case the flexible connection as shown in Fig. 6 has its ends shaped to conform to the contour of the adjacent bucket surfaces.

With either of the arrangements shown, the connections while being flexible enough to permit of expansion and contraction, are sufficiently stiff to tie the bucket groups together so as to prevent their vibration.

By arranging the yieldable connections directly beneath the bucket cover, the periphery of the bucket ring may have the desired clearance with the turbine shell, the connections in no way interfering as they 95 would were they on the outside. Furthermore, there is no danger of the connections rubbing, thereby getting worn or coming loose.

In accordance with the provisions of the 100 patent statutes, I have described the principle of operation of my invention, together with the apparatus which I now consider to represent the best embodiment thereof, but I desire to have it understood that the apparatus shown is only illustrative and that the invention may be carried out by other 105 means.

What I claim as new and desire to secure by Letters Patent of the United States, is:—

1. In an elastic fluid turbine, the combination with a ring of buckets, and a sectional cover tying them together into groups, of means forming flexible connections between adjacent groups, said means being located directly beneath the adjacent ends of bucket cover sections.
- 10 2. An elastic fluid turbine having a rotor with a ring of buckets thereon formed into groups by a sectional bucket cover characterized by the fact that the bucket groups thus formed are tied together by connections in the form of plates located directly beneath the adjacent ends of bucket cover

sections and reversely bent to render them flexible.

3. An elastic fluid turbine having a rotor with a ring of buckets thereon formed into groups by a sectional bucket cover fastened into place by tenons on the ends of the buckets, characterized by the fact that the bucket groups thus formed are tied together by flexible strips located beneath the adjacent ends of bucket cover sections and fastened by the tenons of the adjacent buckets.

In witness whereof, I have hereunto set my hand this 28th day of October, 1920. 30

OSCAR JUNGGREN.
